UNITED STATES PATENT OFFICE.

GUIDO MERLO, OF BRISTOL, PENNSYLVANIA.

MUSIC-ROLL CABINET.

1,396,378.

Specification of Letters Patent.

Patented Nov. 8, 1921.

Application filed March 31, 1921. Serial No. 457,365.

To all whom it may concern:

Be it known that I, GUIDO MERLO, a citizen of Italy, subject of the King of Italy, residing at Bristol, in the county of Bucks and State of Pennsylvania, have invented certain new and useful Improvements in Music-Roll Cabinets, of which the following is a specification.

This invention relates to improvements in cabinets and while designed primarily for embodiment in a cabinet for storing player piano music rolls, may equally as well be employed in cabinets for the storage of various other articles, or in connection with various other articles of furniture embodying two or more drawers arranged one above another.

One of the primary objects of the present invention is to provide means for automatically returning the drawer of a cabinet such as above referred to to closed position after it has been drawn open and the music roll or the like removed therefrom or replaced therein.

Another object of the invention is to provide in a cabinet of the general class mentioned embodying a plurality of drawers arranged one above another, means common to all of the drawers and embodying but a single tension means adapted to automatically return to closed position any one of the drawers which has been drawn open and released.

In the accompanying drawings:

Figure 1 is a front elevation of a cabinet constructed in accordance with the present invention, the door of the cabinet being shown swung open;

Fig. 2 is a vertical front to rear sectional view through the cabinet taken in a vertical plane with one tier of drawers illustrating one of the drawers drawn out to open position;

Fig. 3 is a horizontal sectional view through the cabinet taken in a plane above one row of drawers;

Fig. 4 is a perspective view of one of the drawers removed from the cabinet;

Fig. 5 is a detail view partly in plan and partly in horizontal section illustrating the tension means for returning the drawers to closed position;

Fig. 6 is a vertical transverse sectional view on the line 6—6 of Fig. 5.

The cabinet embodying the invention may be of any desired dimensions and may em-

brace any desired number of drawers arranged in one or more tiers.

The cabinet embodying the invention comprises sides 1, a back 2, a top 3, and a bottom 4, the cabinet being open at its front but provided with a door 5 hinged at one side of the open front, as at 6, and adapted to be swung to position to completely close said front and thus exclude dust from the interior of the cabinet. In order to support the drawers which are housed within the cabinet, a plurality of shelves 7 is arranged within the cabinet one above another and extend between the side walls 1 by which they are supported and extend from the open front of the cabinet rearwardly to a point adjacent the rear wall or back 2 but terminating short thereof so as to provide a space 8 within the rear portion of the cabinet to accommodate and house the drawer tensioning device which will presently be described. Cleats 9 are secured upon the upper sides of the shelves 7 and extend in parallel relation to each other and to the side walls 1 and are suitably spaced to receive and guide between them the drawers which are slidably disposed upon the shelves, and other cleats 10 are secured in vertical parallel position to the forward edges of the shelves and divide, in conjunction with the said forward edges of the shelves, the open front of the cabinet into a plurality of compartments or pigeonholes 11 designed for the individual reception of the drawers of the cabinet. In order to limit the rearward movement of the drawers into the compartments 11, cleats 12 are secured upon the rear edges of the shelves 7 and project slightly above the planes of the upper sides of the respective shelves so as to provide abutments against which the rear ends of the drawers may strike when the drawers are slid inwardly. One of the drawers is clearly illustrated in Fig. 4 of the drawings and indicated in general by the numeral 13 and the same comprises a bottom 14 having upstanding sides 15 which are relatively shallow except at and adjacent their rear ends where they are gradually increased in height, as at 16, and are connected by a rear end wall 17. The forward ends of the sides 15 are connected by a relatively shallow front end wall 18 which may be provided with a finger ring or knob or any other suitable device 19 which may be readily grasped for the purpose of pulling the drawer out-

wardly for the purpose of removing or replacing the music roll or other article to be stored. By reference to Figs. 1, 2 and 3 of the drawings, it will be observed that each 5 drawer 13 is received and housed within a respective one of the compartments 11 and is guided for sliding movement upon the respective shelf which constitutes the bottom of the compartment and between the respective cleats 9 upon the shelf.

10 The drawers are arranged in one or more tiers as previously explained, and in connection with each tier of drawers there is provided means designed to be tensioned when 15 any drawer in the respective tier is pulled to open position and which, when the drawer is released will act upon the drawer to return it to closed or retracted position, and the means referred to comprises a shaft 20 mounted for rotation in suitable bearings 21 within the space 8 at the rear of the cabinet. Secured by a set screw or the like 22 upon the shaft 20 directly opposite the rear end of each drawer 13 is a collar 23 provided upon 25 its periphery with a tooth or shoulder 24. Arms 25 radiate from the periphery of the collar 23 at the lower side thereof and support an annular pulley 26 having a peripheral groove 27, the pulley surrounding the 30 collar and being maintained in concentric relation thereto by providing the arms 25 with upturned outer ends 28 which engage the outer periphery of the pulley 26. The pulley 26 is provided upon its inner periphery 35 with a tooth or shoulder 29 which, upon initial rotation of the pulley in one direction is designed to strike against and coact with the tooth or shoulder 24 of the respective collar 23 to connect these parts for rotation 40 in unison. A coil spring 30 is associated with the shaft 20 and surrounds the same at any convenient point in its length and is secured at one end, as at 31, to the rear wall 2 of the cabinet and at the other end, as at 32, 45 to the said shaft. The spring is so arranged that when the shaft 20 is rotated in one direction it will be tensioned and will tend to rotate the shaft in the reverse direction and will in fact do so when the shaft is relieved 50 of the influence of the rotating means. A cable 33 is connected as at 34 with each drawer 13 at the rear end wall 17 thereof and is wound about the respective pulley 26.

55 From the foregoing description it will be evident that when any one of the drawers in a tier is pulled to open position, the respective cable 33 will be pulled and the respective pulley 26 will be rotated as the cable unwinds therefrom. In this rotative movement 60 of the pulley the shoulder 29 will come into engagement with the shoulder 24 of the respective collar 23 and thus the shaft 20 will be rotated in a direction to place the spring 65 under direct tension. Such rotation of the shaft and the other collars 23 thereon will

not however in any way affect the pulleys 26 which are associated with the other drawers of the tier inasmuch as the shoulders 24 of these collars 23 will be carried in a direction to recede from the shoulders 29 of the respective pulleys. After the drawer has been pulled to open position and the music roll removed therefrom or replaced therein and the drawer is released, the shaft 20 will be immediately rotated in the reverse direction under the influence of the tensioned spring 30, and the cable 33 connected with the drawer will be pulled in a rearward direction thus retracting the drawer to a closed position. In order that the drawer may be permitted 70 to remain in open position for a desired period of time without the necessity of holding it in such position, the shelves 7 are formed in their under sides with transverse grooves 35 in which the upper edges of the 75 rear end walls 17 of the respective drawers may be engaged by a slight tilting of the drawer in a downward direction at its forward end as it is drawn to open position and as clearly illustrated in Fig. 2 of the drawings. 80

85 In order that access may be gained to the various elements comprising the mechanism, the back 2 of the cabinet may be mounted upon hinges 34 and thus adapted to be swung 90 to open position and in this event the bearings for the shaft and other parts which are in the present drawings illustrated as mounted upon the said back, will be supported upon any other suitable fixed means 95 provided for the purpose, as for example horizontal or vertical cleats.

Having thus described the invention, what is claimed as new is:

1. The combination with a cabinet embodying a series of drawers, of means common to all of the drawers operative to automatically return any one of the drawers to closed position when drawn open and released. 105

110 2. The combination with a cabinet embodying a series of drawers, of means common to all of the drawers operative to automatically return any one of the drawers to closed position when drawn open and released, and means for retaining any one of the drawers in open position. 115

120 3. The combination with a cabinet embodying a series of drawers, of a shaft rotatably mounted in alignment with the said series, means for tensioning the shaft when rotated in one direction and operative to reversely rotate the shaft when released, and operative connection between each of the drawers and the said shaft for rotating 125 the shaft in the first-mentioned direction when any one of the drawers is drawn to open position.

130 4. The combination with a cabinet embodying a series of drawers, of a shaft dis-

- posed in juxtaposition to the rear ends of the drawers of the series, operative connection between each of the drawers and the shaft arranged when any one of the drawers 5 is drawn to open position to effect rotation of the shaft in one direction, and means for automatically rotating the shaft in the opposite direction when the drawer is released for return to closed position.
- 10 5. The combination with a cabinet embodying a series of drawers, of a shaft arranged in juxtaposition to the rear ends of the drawers of the series, pulleys upon the shaft arranged one opposite each of the drawers, means for connecting the shaft 15 with any one of the pulleys when the latter is rotated in one direction, a flexible element connected with each drawer and wound upon the respective pulley in a manner to rotate the pulley in the stated direction when the 20 drawer is drawn open, and means for automatically rotating the shaft in the opposite direction when the drawer is released for return to closed position.

In testimony whereof I affix my signature. 25
GUIDO MERLO. [L.S.]
